UNITED STATES PATENT OFFICE.

FREDERICK BERNARD MALCOLM MERCER, OF TORONTO, AND CHARLES FRANKLIN
BRADBURN, OF TILLSONBURG, ONTARIO, CANADA.

MILL-SPOUT GATE.

Application filed September 12, 1919. Serial No. 323,420.

To all whom it may concern:

Be it known that we, FREDERICK BERNARD MALCOLM MERCER and CHARLES FRANKLIN BRADBURN, both subjects of the King of Great Britain, and residents of the city of Toronto and the town of Tillsonburg, respectively, both in the Province of Ontario and the Dominion of Canada, have invented certain new and useful Improvements in 10 Mill-Spout Gates, of which the following is a specification.

The herein described invention relates to a means of controlling mill spout gates where the milling machinery is driven by 15 electric power and where the failure of the power results in the clogging of the milling machinery.

This invention comprises an electro-magnet having a movable armature provided 20 with a detent to engage and hold the gate at any position to which it may be opened and to disengage and release the gate on failure of the power, to be automatically closed through the action of a spring or 25 weight.

The electric apparatus and the connections may be applied to existing gates with slight 30 alterations, but it is thought preferable to attach the same to a special housing containing a gate and gate-way, this housing with its electrical and mechanical apparatus constituting a unit and constructed in such a manner and in such dimensions as to admit 35 of easy application to any standard mill spout through the removal of a section of the same and the fitting of the housing unit within this space.

Figure 1 is a side elevation of the gate housing and attached apparatus.

Figure 2 is a longitudinal section of the electro-magnet with detail.

Figure 3 is an elevation of the armature shield or sleeve.

Figure 4 is an elevation of the armature, 45 extension and detent.

Figure 5 is a cross section of the armature.

Figure 6 is a diagrammatic scheme of the electric circuits.

Figure 7 is a perspective detail of a portion 50 of the spout partly broken away to disclose the gate.

In Figure 1 *a* is the gate housing, which may conveniently be either a metal casting or a sheet metal stamping. This member 55 is provided with a removable head piece *b*

and is secured to the main body by means of bolts *c* passing through flanges *d* formed upon the main body and the head piece. The entire unit is connected with the mill spout *e* by means of bolts or screws *f*, the adjacent upper and lower sections of the spouting abutting if desired internal flanges corresponding to the upper flange of the main body and to the lower flange of bearing *g* of the same. By these means the 60 housing unit *a* may be connected with the mill spouting *e* without subjecting the same to any lateral displacement.

The housing *a* contains a gate-way and gate *t* of conventional design of which *h* is 70 the gate stem.

Mounted upon the housing *a* is a block or post *k*, attached to the housing by the bolts *l* and carrying a lever *m* pivoted to the block at *n* and held under compression by 75 the spring *o*, this spring being connected to the block *k* by the bolt *p*. The lever *m* contains a slot or a cam *q* engaging a pin or pin and roller *r*, carried upon the gate stem *h* so that the gate may be operated 80 manually by means of this lever.

Attached to the housing *a* by the bolts *s* is a curving member *j* having an opening toward its outward extremity through which the gate-stem *h* passes while the lever *m* 85 slidably engages the member *j* on the one side while being held in position against the gate stem *h* on the opposite side, also the gate stem passes through a bushing or collar *v* formed upon the housing *a*. Thus both 90 the lever *m* and the gate stem *h* are well supported and twisting or binding effects upon the gate are avoided. Further the gate-stem *h* carries notches *w* for the purpose hereinafter described.

Lastly there is mounted upon the housing *a* the electro-magnet *x*, being held to the housing by the bolts *y* passing through its end blocks *z* or alternatively the electro-magnet may be attached to a base block 100 which in turn may be attached to the housing.

This electro-magnet *x* actuates a movable armature contained within it and this armature acting through an extension *a*¹ serves 105 as a detent to engage the notches or teeth *w* of the gate-stem *h*, holding the gate at any position desired while power is on and disengaging the notches *w* when the power fails, thus permitting the closing of the gate 110

through the action of the spring o , lever n , etc., the electro-magnet being in electric connection with the service branches furnishing power to the mill.

5 The detail of the electro-magnet x and its particular operation will now be described.

In Figure 2, b^1 shows the coil or winding, c^1 is a sleeve forming a core-piece in which the winding is placed and z are the insulating end blocks for the winding and are pressed upon the sleeve c^1 . Contained within the sleeve c^1 and slidably therein is the moving soft iron armature d^1 .

The armature d^1 is of a length equal to 15 that of the winding b^1 and carries at its outer, or lower end as shown in Figure 2, the extension a^1 which is composed of aluminum or other non-magnetic material, and this extension has formed upon it at its 20 lower or outer end the detent e^1 . The extension a^1 is attached to the armature d^1 by the threaded pin f^1 and has passing transversely through it a pin g^1 by which the armature and detent may conveniently be 25 moved by hand in cases of emergency.

The extension a^1 also carries a screw h^1 for the attachment of a controlling spring.

Attached to the lower end block z of the electro-magnet x , by the screws k^1 , is a conical cap-piece l^1 of brass or other non-magnetic metal, carrying a short sleeve or collar m^1 forming a bearing for the extension a^1 , and containing within its cavity the control coil spring n^1 surrounding the collar m^1 , one end of which spring is attached to 35 the screw h^1 of the armature extension a^1 while the other end is held in a small recess or boring o^1 in the cap l^1 . The function of this spring is to exert an inward or upward 40 pressure upon the extension a^1 .

Attached to the upper end block z of the electro-magnet x by the screw p^1 is a cover plate q^1 of non-magnetic material, protecting the cylindrical cavity r^1 contained 45 within the sleeve c^1 above the armature d^1 , this cover-plate being rotatable about the screw p^1 .

Figure 3 shows a detail of the sleeve c^1 . This sleeve might be formed of wood-fibre 50 tubing but it is preferable to form it of brass or aluminum. It is essential that it should be non-magnetic. As disclosed in the present specification it is of brass and is constructed with longitudinal slots s^1 so as 55 to prevent in as far as possible inductive action of the surrounding coil upon it, the well known action of which would be that the magnetic fluxes generated by the induced currents within the sleeve would oppose and 60 cut down the magnetic lines of force of the inducing currents of the surrounding coil and thereby greatly weaken or practically destroy the magnetic fluxes to be passed through the armature to actuate the latter, 65 or if instead of alternating current, direct

current is being used then it will be a case of the reduction of the total lines of force of the permanent magnetic field and its consequent weakening.

For analogous reasons the armature extension a^1 and the cap piece l^1 are made non-magnetic to prevent distortion of the magnetic field.

In Figure 4 is shown detail of the moving armature d^1 with its extension a^1 and detent 75 e^1 , h^1 being the screw for the attachment of the control spring and g^1 being the transverse pin, each previously mentioned. The armature proper d^1 is grooved or slotted deeply as indicated by j^1 and in the cross 80 section, the purpose of this being to eliminate, or at least reduce to a minimum, the eddy currents set up in the iron along with their heating effect and interference with the useful fluxes passing through the core. 85 The grooving also assists mechanically in the cooling of the armature. Instead of the above structural arrangement of the armature proper a laminated soft-iron armature may be used, but the former design is 90 deemed preferable for the present purpose.

Now having reference to the several drawings the complete action of the apparatus is as follows:

When the coil b^1 is energized by current 95 flowing through it, magnetic lines of force pass through the iron armature d^1 , magnetically polarizing the same and the tension along these lines of force draw or attract the armature etc., downwardly against the 100 action of the control spring n^1 until its ends coincide with the planes or lines bounding the extremities of the coil b^1 , thus causing the detent e^1 on the armature extension a^1 to engage one of the notches or teeth w upon 105 the gate-stem h and hold the said stem and its gate at any position to which it may be moved by the lever m .

Upon failure of the power and de-energizing 110 of the coil b^1 , the magnetic field acting upon the armature d^1 is of course reduced to zero and the now de-polarized armature is retracted by the control spring m^1 until the screw h^1 abuts the face of the lower end block z of the coil b^1 in which position the 115 upper end of the armature d^1 will register with the straight line v^1-v' drawn across the coil perpendicular to its axis, and lying within the cavity r^1 , this movement resulting in the disengagement of the detent e^1 from the notch w and the consequent closing of 120 the mill spout gate.

As hereinbefore in part described, the terminals of the coil b^1 of the above electric apparatus are connected to the service 125 branches supplying power to the mill through a "step-down" transformer.

In Figure 6 the general scheme of the electric circuits is indicated. In the figure w^1 represents the service branches leading 130

into the mill, x^1 a transformer, y^1 , y^1 the local circuit leading to the electro-magnets w which are coupled in parallel across the local line y^1 , y^1 , and z^1 and a^1 indicate respectively a main switch and a fuse located upon the ordinary switchboard.

The shunt lines b'' across the branch y^1 may be carried through secondary switches c'' to admit of the independent cutting out 10 of the local units x . The terminals or binding posts of the local units are indicated by d'' .

The switches c'' are specially designed to give condenser effects and obviate sparking 15 on opening up the contacts and in addition the contacts have a dust proof cover plate screwed over them, the objects of these precautions being the elimination of the danger of explosion of mill dust. Where the mill 20 spouts are metallic throughout, the entire housing unit of this apparatus may well be insulated.

The local units x may of course be connected to the service branches w^1 without 25 passing through a transformer, a resistance coil, in this case being cut in at the switchboard on one side of the local line y^1 , but this results in a wastage of current and is not so satisfactory.

30 In those exceptional cases where the electric power is direct current, it is obvious that the above arrangement, i. e., the like employment of a special resistance to reduce the current becomes imperative. In the use 35 of direct current the electro-magnets w might be designed to give a very high resistance through their coils b^1 , etc., and the special resistance dispensed with but this would be very disadvantageous practice 40 from an engineering view point.

What we claim is:

1. In mill spout gates, a gate valve having a stem extending therefrom, a housing for said valve, means for operating said 45 valve and automatic means for closing said valve coincident with the stoppage of the said mill machinery with which it is adapted to co-operate.

2. In mill spout gates, a gate valve having a stem extending therefrom, a housing for said valve, means for operating said valve, and electro-magnetic means adapted upon de-energization to permit of the closing of said valve co-incident with the stoppage 55 of the mill machinery with which it is adapted to co-operate.

3. In mill spout gates, a gate valve having a stem extending therefrom, a housing for said valve, means for operating said 60 valve and electro-magnetic means operatively connected to said stem and adapted to recede therefrom on de-energization to permit the closing of said valve co-incident

with the stoppage of the mill machinery with which it is adapted to co-operate. 65

4. In mill spout gates, a gate valve having a stem extending therefrom, a housing for said valve, manually operated means for raising said valve and electro-magnetic means adapted to be de-energized co-incident 70 with the stoppage of the mill machinery with which it is adapted to co-operate for co-incident closing of said valve.

5. In mill spout gates, a gate valve having a stem extending therefrom, a housing for said valve, manually operated means for raising said valve, electro-magnetic means operatively connected to said stem adapted upon de-energization consequent upon the stoppage of said mill machinery, to permit 80 of the closing of said valve coincident with the stoppage of said machinery, with which it is adapted to co-operate, and automatic means adapted on the action of said electro-magnetic means to quicken the closing of 85 said valve.

6. In mill spout gates, a housing, a gate valve having a ratchet stem extending through said housing, a guide for said stem, a post projecting from said housing, a lever 90 pivoted to said post and adjustably engaging said stem for raising said valve, electro-magnetic means normally in operative engagement with said ratchet stem and a main electric circuit suitably energized and including various translating devices, and said electro-magnetic means. 95

7. In mill spout gates, a housing, a gate valve having a ratchet stem extending through said housing, a guide for said stem, a hand lever operatively connected to said stem, spring means exerting inward pressure on said lever to close said gate, an electric circuit, an electro-magnet connecting with said electric circuit and comprising a 100 core piece adapted to carry windings, end blocks carried by said core piece, a movable armature slidable within said core piece and having a non-magnetic extension therefrom, a detent carried by said extension and 110 adapted normally to engage said ratchet stem, a cap secured over one end of said electro-magnet and slotted to slidably accommodate said extension and a spring located within said cap and exerting inward 115 pressure on said extension to disengage said detent from said ratchet stem upon the de-energization of said electro-magnet.

Signed at the city of Toronto, Province of Ontario, this 12th day of August, 1919. 120
